FOLDING TABLE

John Kovats, Fairfield, Conn.

Application April 14, 1936, Serial No. 74,237

14 Claims. (Cl. 311—82)

This invention relates to folding tables, and especially card or game tables of the type described and claimed in my Patent No. 2,005,716, June 18, 1935, wherein there is disclosed means for supporting folding legs in both extended and folded position and for maintaining said positions, and also operating connections for effecting conjoint positioning of all the legs.

It is an object of the present invention to provide improved operating connections for effecting positioning of all the legs of the table through the manual operation of any one of the legs, and for providing improved connections such that when the legs are locked in extended position all may be released to be folded by the release of any one.

A feature of the present invention is the provision of operating connections, for all four legs, which are removed from the vicinity of the marginal portions of the table so that there is no danger of pinching of the fingers when holding the table and operating the legs thereof.

Other features and advantages will hereinafter appear.

25 In the accompanying drawings:

Figure 1 is a bottom plan view of a table made in accordance with this invention, with the legs in folded position.

Fig. 2 is a fragmentary detail plan of one corner 30 of the table, with the leg folded against the table top.

Fig. 3 is a fragmentary view of one corner of the table in vertical section on line 3—3 of Fig. 2.

Fig. 4 is a fragmentary view of one corner of 35 the table in vertical section with the leg extended. This figure is taken on the line 4—4 of Fig. 5 following.

Fig. 5 is a plan view of the table corner of Fig. 4, the leg being sectioned on line 5—5 of Fig. 4.

40 As shown in the accompanying drawings, the present invention is applied to a card table of the type wherein legs 10 fold perimetrically within a marginal frame 11 of the table top 12, the underside of which is shown in Fig. 1. Each leg is secured to a plate 13 having a barrel 14 receiving a pin 15 carried by a bracket 16. The bracket 16 is fastened in the corner formed by the inner sides of the frame 11.

The legs 10 are moved from folded position 50 shown in Figs. 2 and 3 to extended position shown in Figs. 4 and 5 by an actuating mechanism including for each leg a pair of links 17 and 18 hinged together at 19. The links are connected respectively to the legs and the table by pins 20 and 21, and are positioned so as to lock the legs

when in extended position, and each link 18 has an arcuate slot 22 in which rides a pin 23 carried by the bracket 16, so that the movement of the link is limited thereby.

Each toggle link 18 is connected to a spring 24 having its other end shaped to form a loop which bears against the bracket 16, the spring being held by a pin 25 attached to the marginal frame 11. The spring 24 acts to urge the links 17 and 18 to either folded or extended straight positions, depending on whether the moving end of the spring lies above or below the pin 21. Thus the spring may urge the leg into either extended or folded position from a dead center position intermediate these positions (refer to Figs. 3 and 4). 15

When the legs are in extended position and it is desired to fold them inwardly, the toggle links 17 and 18 are broken from their locked position by an actuating lever 26 carried by the pin 21, which forces the link 18 inwardly toward the table top 20 when the lever is actuated.

The actuating mechanism thus far described may be operated by moving each leg separately, from its folded to its operative or extended position, and forms subject matter in my Patent No. 2,005,716 above referred to. There is also disclosed in this patent a common actuating device for linking the motions of all four legs, and the present invention is primarily concerned with an improvement of said actuating device. 25

According to the present disclosure there is provided as shown in Figs. 1 to 5, means associated with each set of diagonally opposite legs for connecting the links 18 of said legs so that movement of one leg causes corresponding movement 35 of the leg diagonally opposite it, these means including pairs of links extending under the table diagonally thereof, and connected to levers engaging the links 18.

For this purpose there are provided, engaging the links 18, actuating levers 27, which are pivotally carried by pins 28 set in the bracket plates 16, and said levers each have apertured arms 29 and 30 of equal length, and an extension 31 having an upturned arcuate flange 32 with a center of curvature in the pin 28. The extension 31 is provided with a recess 33 which opens into a slot 34 dividing the flange in two parts, and a pin 35 carried by the link 18 engages said slot so as to form a gear-connection between 40 the link and the lever 27. In effect, the lever 27 acts as a two-tooth contrate wheel, and the link 18 and pin 35 as a one-tooth pinion, each engaging the other to coordinate the movements of the lever and link. It will be readily seen that with 45 50 55

the leg and links 17 and 18 folded, the lever 27 will be in a position as shown in Fig. 2, and with the leg and links extended the lever will be positioned as in Fig. 5.

5 According to the at present preferred form of the invention, the levers 27 which are diagonally opposite each other are pin-connected by pairs of long links 36, so that movement of one lever of a pair causes corresponding movement of the 10 other lever, and therefore the legs diagonally opposite each other have their movements co-ordinated in like manner.

The table as described thus far may be satisfactorily operated, it being required to manually 15 actuate only two adjacent legs in order for all the legs to be actuated. Thus to set up the table for use, the upper leg of Fig. 1 may be extended by hand, whereupon the lower leg will also be extended, and the left leg may be extended by 20 hand, whereupon the right leg will also be extended.

When it is desired to fold the legs, one of the actuating levers 26 is pulled outwardly, moving 25 the link 18 which it engages, which link in turn, moves its associated lever 27, the links 36, and the lever 27 at the diagonally opposite corner of the table, which breaks the locking action of the toggle links for the diagonally opposite leg, so that both legs will simultaneously fold inward. 30 Any one of the levers associated with the two remaining extended legs may be likewise actuated to simultaneously unlock said legs similarly, whereupon they may be also folded inwardly.

However, in order to further facilitate the 35 opening and closing of the table, the links 36 are all connected so that their movements are coordinated whereby one table leg may be manually actuated to cause the remaining three legs to be similarly actuated.

40 As shown in Fig. 1 this is accomplished by providing a floating connector 37 having four apertured arms which are pin-connected to the links 36. Movement of any pair of links 36 causes a turning of the connector 37 which in 45 turn causes movement of the other pair of links.

Thus the legs are connected for conjoint movement and positioning of all by any one, and all of the legs may be simultaneously unlocked by actuating any one lever 26 to cause simultaneous 50 movement of all the levers 27, and breaking of all of the toggle links 17 and 18, whereupon movement of any one leg into folded position will result in movement of all the legs in folded position.

55 It should be understood that in the broader aspects of the invention each pair of diagonally opposite levers 27 may be connected by only one link 36, suitable means being employed to connect the crossing links together so as to coordinate their movements, and other variations and modifications may be made within the scope of the invention and portions of the improvements used without others.

I claim:

65 1. In a folding table, the combination of a rectangular table top; four legs; means for hinging the legs on the table top at the corners thereof for movement to and from extended and folded positions; toggle links connecting each leg with the table top; and means acting on said toggle links for interconnecting the legs for simultaneous movement of all by one, said means including two pairs of link members disposed diagonally of the table top, each pair interconnecting 70 diagonally opposite toggle links, and a con-

5 nector having apertured arms pin-connected to the link members.

2. In a folding table, the combination of a rectangular table top; four legs; means for hinging the legs on the table top at the corners thereof for movement to and from extended and folded positions; toggle links connecting each leg with the table top; and means acting on said toggle links for interconnecting the legs for simultaneous movement of all by one, said means including two pairs of link members disposed diagonally of the table top, each pair interconnecting diagonally opposite toggle links, and including means interconnecting the pairs of diagonally disposed link members with each other. 10 15

3. In a folding table, the combination of a rectangular table top; four legs; means for hinging the legs on the table top at the corners thereof for movement to and from extended and folded positions; toggle links connecting each leg with the table top; and means acting on said toggle links for interconnecting the legs for simultaneous movement of all by one, said means including a two tooth contrate gear associated with each pair of toggle links, and engaging a 20 25 tooth carried by one of said pair of links.

4. In a folding table, the combination of a rectangular table top; four legs; means for hinging the legs on the table top at the corners thereof for movement to and from extended and folded 30 positions; toggle links connecting each leg with the table top; means associated with one pair of diagonally opposite toggle links for interconnecting the legs connected therewith for simultaneous movement of both by one; means associated 35 with the other pair of diagonally opposite toggle links for interconnecting the legs connected therewith for simultaneous movement of both by one.

5. The invention as defined in claim 4, in which each means associated with a pair of diagonally 40 opposite toggle links includes at least one link member disposed diagonally of the table top.

6. The invention as defined in claim 4, in which each means associated with a pair of diagonally opposite toggle links includes at least one link 45 member disposed diagonally of the table top, and in which there is means interconnecting the diagonally disposed link members so that movement of one leg will cause simultaneous movement of all the other legs. 50

7. The invention as defined in claim 4 in which each means associated with diagonally opposite toggle links for interconnecting the legs includes at least one link extending diagonally of the table top; and in which there is means for connecting 55 said link or links to the toggle links.

8. The invention as defined in claim 4, in which each means associated with diagonally opposite toggle links for interconnecting the legs includes at least one link extending diagonally of the table 60 top; and in which there is means of connecting said link or links to the toggle links, said means including a two-tooth contrate gear engaging a tooth carried by a toggle link.

9. In a folding table, the combination of a 65 rectangular table top; four legs; means for hinging the legs on the table top at the corners thereof for movement to and from extended and folded positions; four pairs of toggle links, each pair connecting one leg with the table top, the toggle 70 links carried by the table top each having a pin extending therefrom; four levers, each pivotally mounted in one corner of the table top, and each having an arcuate flange with a recess therein for engagement with the pin of the toggle link 75

carried by the table top; a pair of link members connecting one set of diagonally opposite levers, and a pair of link members connecting the other set of diagonally opposite links so that movement of any one leg of the table results in corresponding movement of the leg diagonally opposite to it.

5 10. In a folding table, the combination of a rectangular table top; four legs; means for hinging the legs on the table top at the corners thereof for movement to and from extended and folded positions; four pairs of toggle links, each pair connecting one leg with the table top, the toggle links carried by the table top each having a pin extending therefrom; four levers, each pivotally mounted in one corner of the table top, and each having an arcuate flange with a recess therein for engagement with the pin of the toggle link carried by the table top; a pair of link members connecting one set of diagonally opposite levers, and a pair of link members connecting the other set of diagonally opposite links so that movement of any one leg of the table results in corresponding movement of the leg diagonally opposite to it; and means for interconnecting each pair of link members so that movement of one pair causes corresponding movement of the other pair in order to effect conjoint positioning of all the legs through positioning of any one leg.

11. The invention as defined in claim 10, in which the means interconnecting the link members includes a full floating connector having four apertured arms pin-connected to said link members.

12. In a folding table, the combination of a rectangular table top; four legs; means for hinging the legs on the table top at the corners thereof for movement to and from extended and folded positions, including four bracket plates carried by the table, one plate in each corner of the table; four pairs of toggle links, each pair connecting one leg with a bracket plate, the toggle links carried by the bracket plates each having a pin extending therefrom; four levers, each pivotally

mounted in one corner of the table top on a bracket plate, each lever having an arcuate flange with a recess therein for engagement with the pin of the toggle link mounted on the bracket; a pair of link members connecting one set of diagonally opposite levers, and a pair of link members connecting the other set of diagonally opposite links so that movement of any one leg of the table results in corresponding movement of the leg diagonally opposite to it.

10 15 13. In a folding table, the combination of a rectangular table top; four legs; means for hinging the legs on the table top at the corners thereof for movement to and from extended and folded positions; toggle links connecting each leg with the table top; and means acting on said toggle links for interconnecting the legs for simultaneous movement of all by one, said means including two link members, each associated with a pair of diagonally opposite toggle links, an interconnecting member pivotally connected with said link members, and means for causing the interconnecting member to rotate upon movement of one of the said link members whereby movement of one link member is effected simultaneously with movement of the other link member.

20 25 30 35 14. In a folding table, the combination of a rectangular table top; four legs; means for hinging the legs on the table top at the corners thereof for movement to and from extended and folded positions; toggle links connecting each leg with the table top; and means acting on said toggle links for interconnecting the legs for simultaneous movement of all by one, said means including a plurality of link members, each associated with one of the toggle links for the legs, an interconnecting member pivotally connected with all of said link members, and means for causing the interconnecting member to rotate upon movement of any one link member whereby movement of all link members is effected simultaneously with movement of any one link member.

40 JOHN KOVATS.
